(57) **CLAIM**

The ornamental design for an eye shield for sleeping, or the like, as shown and described.

DESCRIPTION

FIG. 1 is a perspective view of a person using the invented eye shield for sleeping, and showing the new design;

FIG. 2 is a perspective view of the invented eye shield for sleeping, and showing the new design in greater detail;

FIG. 3 is a rear elevational view thereof;

FIG. 4 is a top view thereof;

FIG. 5 is a left side elevational view thereof;

FIG. 6 is a front elevational view thereof;

FIG. 7 is a right side elevational view thereof; and,

FIG. 8 is a bottom view thereof.

Material shown in dotted lines is for clarity only, and forms no part of the invented design.
